UNITED STATES PATENT OFFICE.

ANTOINE FRANÇOIS DÉVIGNE AND JEAN PIERRE DURAND, OF LA COUR-DU-PIN, FRANCE.

WEFT STOP-MOTION FOR LOOMS.

SPECIFICATION forming part of Letters Patent No. 449,283, dated March 31, 1891.

Application filed June 20, 1890. Serial No. 356,169. (No model.) Patented in France October 27, 1886, No. 179,169; in Belgium November 13, 1886, No. 75,223; in England December 30, 1886, No. 17,094; in Italy December 31, 1886, XLI, 227; in Spain January 3, 1887, No. 10,314, and in Germany November 19, 1887, No. 51,464.

To all whom it may concern:

Be it known that we, ANTOINE FRANÇOIS DÉVIGNE and JEAN PIERRE DURAND, of the city of La Cour-du-Pin, France, have invented 5 Weft-Stop Motions for Looms, (for which we have obtained Letters Patent in France for fifteen years, dated October 27, 1886, No. 179,169; in Belgium for fifteen years, dated November 13, 1886, No. 75,223; in Great Britain for fourteen years, dated December 30, 1886, No. 17,094; in Italy for fifteen years, dated December 31, 1886, No. 227, Vol. 41; in Spain for twenty years, dated January 3, 1887, No. 10,314, and in Germany for fifteen years, 15 dated November 19, 1887, No. 51,464,) of which the following is a full, clear, and exact description.

This invention relates to an improved weft stop-motion for power-loom, the distinguishing 20 feature of which is that the weft is kept at a uniform tension while it is being beaten up into the fabric, whereby the latter is more closely woven with a less consumption of weft, whereas in the old looms the weft is 25 pushed away more or less from the goods by the weft-fork and is consequently beaten up in a more or less slack condition.

Reference is to be had to the accompanying 30 drawings, forming part of this specification, wherein—

Figures 1 and 2 show in front and side elevation as much of the loom as is necessary to illustrate the weft stop-motion. Fig. 3 is a rear elevation of the driving mechanism of 35 the loom. Fig. 4 shows an elevation of the weft-fork on a larger scale in the position it occupies on seizing the weft after the boxing of the shuttle. Figs. 5, 6, and 7 illustrate the working of the weft stop-motion. Fig. 8 is a 40 sectional plan view of the loom, showing the cam and its driving mechanism shown in Fig. 1.

r's are pairs of grids, one pair at each side of the loom, the grids being arranged one 45 above the other between the reed *n* and the shuttle-boxes *b*', and actuated in such manner that they grasp and hold the weft in tension immediately after each passage of the shuttle through the shed, as shown in Fig. 4,

while in the absence of weft the bars of the 50 upper grid *r* will fall between those of the lower grid *s* and immediately cause the knock-off of the loom. The upper grid *r* of each pair is carried at one end of a light lever pivoted at *r'* on the batten and terminating at the 55 other end in a hook-shaped catch *r*², Figs. 2, 5, 6, and 7. The lower grid *s* is fixed to a vertically-movable slide *s'*, mounted on the front of the batten, and is moved upward immediately after the laying in of the weft by the tension of 60 a spring *s*², acting on a lever *s*³, Figs. 2, 5, 6, and 7, which is permitted to come into action at the proper moment, as hereinafter described. The motion of the weft on the one hand and the object to be attained by the grids permit 65 of definite positions of these grids *r* and *s* during the weaving. The grids are only permitted to close together after the laying in and during the beating up of the weft. At other times the grids must be separated, and 70 for this purpose the operation of the grids is controlled by the cam *t*, Figs. 1, 2, and 8, fast on the shaft *g*, which has a concentric depression extending around about a fourth of its circumference, and is actuated through 75 the bevel-wheels *g'* from the main shaft of the loom *k*. The cam *t* acts on friction-rollers carried at the upper ends of levers *t'*, that are drawn toward said cam by a spring *w*. The lower ends of the levers *t'* are connected 80 by means of bell-crank levers *t*² and rods *t*³ with vertically-movable slides *u*, each having two lugs *r*³ and *s*⁴, respectively, acting periodically on levers *r*² and *s*³, and putting spring *s*² in tension. As long as the corresponding friction-roller bears against the highest part of the cam, the lug *s*⁴ depresses the lever *s*³ and the lug *r*³ acts on the lever *r*² and raises grid *r*, as shown in Fig. 5. When 85 the friction-roller falls into the depression of the cam the slide *u* rises. This takes place directly the shuttle is boxed at that side of the batten, which is then in its backward position. When the slide *u* releases the levers *r*² and *s*³, the grid *r* falls down upon the weft, 90 but the lower grid *s* is prevented from rising (by a vertical tail-piece or projection *s*⁷ of the lever *s*³ abutting against a stationary stop *s*⁵,

Figs. 2, 5, 6, and 7) until the batten has commenced its forward motion, whereupon the tail-piece s^7 moves away from the stationary abutment s^5 , and the lower grid s is raised by the action of the spring s^2 until it meets the weft just laid between it and the upper grid, the weft being thereby nipped between the two grids, as shown in Figs. 4 and 6, so that it is held taut during the beating up, thus producing a close texture and effecting an economy of yarn.

Fig. 6 shows how the presence of the weft between the grids keeps the hook r^2 out of reach of the catch v of the mechanism for actuating the belt-shipper and stopping the loom. Should the weft be broken or absent, or the shuttle be trapped in the shed, the upper grid being unsupported will drop into the lower grid, as shown in Fig. 7, and the hook r^2 will be raised into position for engagement with the hook v , so as on the beating up of the batten to cause the belt to be thrown off and the loom to be instantly stopped.

The knocking-off mechanism of the loom is shown in Fig. 2 and comprises the catches v , each carried by a lever s , mounted on a fixed center and connected by rod 4, spring 3, and lever-arm 1^a with a rock-shaft v' . On this shaft v' is loosely mounted an arm 1, carrying a spring-pressed catch v^2 , adapted to engage with a trigger v^3 and swing it from the normal position into the position shown, which is in a path of a lug v^4 on the periphery of a wheel v^4 , fast on the main shaft K. The trigger v^3 is pivoted to a vertically-sliding bar v^5 , which, on the trigger v^3 being struck by the lug v^4 , is slid upward in its guides and acts on an elbow-lever v^6 , Figs. 2 and 3, connected at its lower end with the belt-shipper v^9 , whereby the belt is thrown on the loose pulley i' . Further rotation of the shaft K is prevented by the abutment of the lug v^4 against the trigger v^3 . The lever-arm 2, which supports the rod 4, is keyed on the rock-shaft v' , and the spring 3, connecting the arm 1^a with the rod 4, prevents any possibility of breakage of the mechanism should the batten continue its motion after the knocking off, as the rod 4, which may be supported by the arm 2 by resting in the forked

upper end of arm 2 for the purpose of keeping rod 4 from falling, may move without pulling the arm 1^a , since there is only a spring 3 connecting them, said spring being only strong enough to overcome the ordinary resistance occasioned in the regular working of the machine. The attendant can also stop the loom by pushing the rod v^7 , Fig. 2, which is within easy reach near the starting-lever.

By referring to Fig. 3 it will be seen that the belt-shipper rod v^9 extends entirely across the loom and acts simultaneously on a clutch x , connected by groove and feather with the main shaft, the belt-shipper rod terminating for this purpose in an enlargement x' , passing between two friction-rollers, of which the axis of one x^2 is fixed and that of the other x^3 is carried by one arm of an elbow-lever x^4 , and of which the other arm is forked and embraces the grooved collar of the clutch x . When the enlargement x' is between the pulleys $x^2 x^3$, the clutch is disengaged, and this is the normal position of working, the belt-shipper being then opposite the fast pulley; but when the belt is thrown onto the loose pulley the clutch is thrown into gear, and so enables the workman to drive the loom slowly by hand through the medium of the hand-wheel y , the inclined shaft y' , and bevel-gears y^2 .

We claim—

In a weft stop-motion for looms, the combination of two vertically-movable grids r and s , the upper grid r being adapted to drop by gravity and the lower grid s being sliding with the spring s^2 , lever s^3 , its tail-piece s^7 , stop s^5 , the slide-bar u , having the stops r^3 and s^4 and the lever r^2 and catch v , substantially as herein shown and described.

The foregoing specification of our weft stop-motion for power-looms signed by us this 23d day of May, 1890.

ANTOINE FRANÇOIS DÉVIGNE.
